UNITED STATES PATENT OFFICE.

SAMUEL J. MURRAY, OF CINCINNATI, OHIO, ASSIGNOR TO THE RUSSELL & MORGAN PRINTING COMPANY, OF SAME PLACE.

MACHINE FOR CUTTING CARD-BOARD.

SPECIFICATION forming part of Letters Patent No. 310,534, dated January 6, 1885.

Application filed September 1, 1883. (No model.)

To all whom it may concern:

Be it known that I, SAMUEL J. MURRAY, of Cincinnati, Hamilton county, Ohio, have invented a new and useful Improvement in Machines for Cutting Printed Sheets of Card-Board or Pasteboard into Strips, of which improvement the following is a specification.

My invention is particularly designed for machines employed for separating into single columns of prints (preparatory to punching) a sheet of pasteboard or card-board imprinted with a congeries of designs or pictures—such, for example, as go to make up a "pack" or "deck" of playing-cards. In machines of this class commonly employed the sheet is fed directly in between the feed-rollers, and accuracy of cutting is made to depend on two causes, both variable and imperfect—to wit, first, an extremely skillful manipulation, and, secondly, strict rectangularity and uniform thickness of the advancing sheet-edge to the lines of demarcation between the rows or columns of prints to be separated from one another. The difficulty of securing these pre-

requisites causes many sheets to be spoiled in the act of cutting by the running of the cuts over the printed matter, or so near to it as to destroy merchantable symmetry of the finished cards. I overcome this difficulty by a provision by which the act of the operator which slips the drive-belt onto the loose pulley is made effective to simultaneously elevate the pressure-roller, thus enabling the attendant to arrange the sheet in strict alignment with the gage while its forward portion is well advanced under said roller, so that on starting the machine the roller closes automatically down upon the sheet at right angles to the demarcations, with the result of feeding the sheet in strict parallelism thereto, no matter how much out of truth the front edge may be.

In the accompanying drawings, Figure 1 is a perspective view of a machine embodying my improvements, (portions of the pulleys being broken away,) the belt occupying the loose pulley and the upper feed-roller being consequently elevated. Figs. 2 and 3 are vertical sections of the feeding, cutting, and delivery members in their inoperative and operative conditions, respectively. Fig. 4 shows

the geared connections of the rotating members. Fig. 5 shows the connecting-gears of the treadle and the belt-shifter detached.

A may represent any suitable frame, to which are firmly attached the feed board or platform B, the delivery-chute C, and the guides or tracks G. Journaled in bearings in the frame are the delivery-rollers D E and the feed-roller F. Journaled in one vertical plane are the shafts H and I of two coating gangs of rotary cutters, J K. The shaft H carries fast and loose pulleys L L', which operate in customary manner with a driving-belt, M, provided with a belt-shifter, N. The shaft H is connected by gearing O to the feeding-rollers, the cutter-shafts, and the lower delivery-roller, respectively. The belt-shifter N is connected by rack P with a pinion, Q, upon the shaft R of a treadle, S, whose normal or inactive position (see Fig. 1) is secured by a spring, T. This position of the treadle corresponds to a position of the shifter N, which holds the belt upon the loose or inactive pulley L.

To the above-described parts, which may be substantially similar to parts of like functions on machines heretofore in use, I add, for the purpose of securing absolute accuracy of cuts, the following devices: A pressure-roller, U, is so journaled in brackets V, secured by hinges v to the platform, as in its lower position (see Fig. 3) to rest upon the feed-roller F. When the treadle mechanism is in the condition it assumes if left at liberty, (in which the belt-shifter is held in the vicinity of the loose pulley, and in which the machine is consequently at rest,) the said pressure-roller U is elevated from the feed-roller (see Figs. 1 and 2) by the means following: Cranks W on the treadle-shaft R (connected by rods X to the brackets V, in which the pressure-roller is journaled) are so located upon said shaft as, in the said free condition of the treadle mechanism, to elevate the brackets, and consequently the pressure-roller, in the manner shown in Figs. 1 and 2, and so as, in the depressed condition of the treadle, to forcibly depress the said pressure-roller a little in advance of resumption of its rotation, as shown in Fig. 3.

To enable the attendant to place the sheet 100

accurately upon the platform, I provide two gage-fingers, of which finger 1 is attached by set-screw 2 to a stretcher, 3, of the frame near the rear of the platform, and of which the 5 other finger, 4, is attached by set-screw 5 to a shaft, 6, which is journaled in bearings 7 near the front of the platform, and is provided with a handle, 8. These two fingers, having been accurately adjusted in alignment with a 10 central cutter, are fixed to such adjustment by tightening of the set-screws 2 and 5. While the machine is at rest, the attendant, taking the sheet in one hand, with the other hand momentarily elevates the nearer finger 15 4 by means of handle 8, and so arranges the sheet upon the platform as to bring the printed guide-mark upon the sheet coincident with the fingers, and its forward portion underneath the elevated pressure-roller. Depression, now, of the treadle operates first to 20 bring the pressure-roller forcibly down upon the sheet, and while said roller continues thus depressed to rotate all the revolving members, as indicated in Figs. 3 and 4, causing 25 the sheet to be fed forward, cut, and delivered in the condition of narrow strips.

I claim as new and of my invention—

1. In a machine for cutting printed sheets into strips, the combination, with a rotary gang of cutters and with a feed-roller, of the 30 pressure-roller U, having the described connection P Q R V W X with the belt-shifting mechanism, so as to be lifted from the feed-roller, and to be caused to rest thereupon by the respective acts of stopping and starting 35 the machine, substantially as and for the purposes set forth.

2. In a machine for cutting printed sheets into strips, the combination, with a platform, a rotary gang of cutters, and a feed-roller, of 40 a belt-shifter and a pressure-roller, which are so geared, substantially as described, to said treadle-shaft as for said pressure-roller to rise and fall with changes in elevation of the treadle, as and for the purpose set forth. 45

In testimony of which invention I hereunto set my hand.

SAMUEL J. MURRAY.
